UNITED STATES PATENT OFFICE.

ADOLPH C. RECKER, OF OAKVILLE, CONNECTICUT, ASSIGNOR TO CHASE CO'S INC., OF WATERBURY, CONNECTICUT, A CORPORATION.

ACETYLENE MINER'S LAMP.

Application filed June 26, 1923. Serial No. 647,809.

To all whom it may concern:

Be it known that I, ADOLPH C. RECKER, a citizen of the United States, residing at Oakville, in the county of Litchfield and State 5 of Connecticut, have invented a new and useful Improvement in Acetylene Miners' Lamps; and I do hereby declare the following, when taken in connection with the accompanying drawings and the characters of 10 reference marked thereon, to be a full, clear, and exact description of the same, and which said drawings constitute part of this application, and represent, in—

Fig. 1 a view in front elevation of an 15 acetylene miner's lamp embodying my invention.

Fig. 2 a view thereof in side elevation.

Fig. 3 an enlarged broken view in vertical section.

20 Fig. 4 a detached broken view on the same scale of the reflector, with its swivelled nut.

Fig. 5 a detached view on the scale of Figs. 1 and 2 of the reflector-supporting shell.

25 My invention relates to an improved acetylene miner's lamp, the object being to provide simple, convenient and reliable means for mounting the reflector thereof and securing it in place against displacement.

30 With these ends in view, my invention consists in an acetylene miner's lamp characterized by having the nut, by which the reflector of the lamp is secured in place, mounted in the reflector in which it swivels.

35 My invention further consists in an acetylene miner's lamp characterized as above and having positioning means for preventing the reflector from turning with respect to the shell, whereby the sparking-wheel is maintained in predetermined position.

40 My invention further consists in an acetylene miner's lamp having certain details of construction and combinations of parts as 45 will be hereinafter described and particularly pointed out in the claims.

45 In carrying out my invention, as herein shown, I employ a lamp-body consisting of a cylindrical carbide-receptacle 10, and a 50 water-chamber 11 superimposed thereupon and provided with a domical cap 12 having a filler-cap 13 and swept by the usual valve-lever 14. The lamp is also provided with the usual externally-threaded burner-stem 55 15 projecting outwardly from the water-

chamber 11 at a right angle to the vertical axis of the lamp, which in its form and details may be of any standard construction.

For securing the reflector 16 in place, I employ a nut 17 provided at its inner end 60 with an outwardly-turned retaining-flange 18, the nut being in this manner permanently connected with the reflector, so as to freely swivel therein, for being screwed upon, or unscrewed from, the threaded burner-stem 65 15.

For supporting the reflector firmly with respect to the lamp-body and against canting in any direction, I employ a struck-up sheet-metal supporting- or backing-shell 19, 70 circular or cup-shaped in general form, but having its bottom shaped, as shown in Figs. 2 and 3, to conform to the external contour of the water-chamber 11, whatever the contour of the same may be, the said 75 shell being preferably secured to the water-chamber and formed with an opening 20, through which the stem 15 projects outward from the body. It will be sufficient to secure the shell by a drop of solder to the 80 lamp-body, or it may be secured thereto in some other manner, or left free. But whatever the contour of its bottom, which should conform to the exterior contour of the water-chamber, its flanged outer edge 21 will lie 85 in the same vertical plane, so that, when the nut 17, carried by the reflector, is screwed over the stem 15, the reflector will be positioned and firmly held in the vertical plane.

In order to prevent the reflector from 90 turning, it is preferably provided upon its rear face with a boss or nib 22, for entrance into a positioning-notch 23 in the flange 21 of the shell 19.

Before the nut 17 is turned home on the 95 stem 15, the nib 22 is aligned with the notch 23, so that, when the nut is turned home, the said nib and notch will co-act to prevent the reflector from turning. Incidentally, the said boss and notch insure a predetermined location for the sparking-wheel 24, which is mounted in the usual manner in a slotted stud 25 in the reflector.

By permanently mounting the nut 17 in the reflector 16, so as to swivel therein, its 105 loss is prevented and its convenient manipulation secured, while by providing means for predetermined the position of the reflector and for holding it in such position, it is guarded against being accidentally 110

rotated, as, for instance, by the collision of its edge with any overhead obstruction when the lamp is in the hat of the miner.

I claim:

- 5 1. In an acetylene miner's lamp, the combination with the lamp-body and threaded burner-stem thereof, of a reflector, and a swivelled nut non-removably mounted therein for engagement with the said stem, 10 the said nut projecting forwardly into the reflector for manual operation from the inside thereof.
- 15 2. In an acetylene miner's lamp, the combination with the lamp-body and threaded stem thereof, of a reflector, a reflector-supporting shell interposed between the reflector and the lamp body, and a swivelled nut non-removably mounted in the reflector for engagement with the said stem, whereby 20 the reflector is firmly seated upon the said shell, the said nut projecting forwardly into the reflector for manual operation from the inside thereof.
- 25 3. In an acetylene miner's lamp, the combination with a lamp-body comprising a carbide-receptacle and a water-chamber, of a threaded burner-stem projecting from the said water-chamber, a reflector, a reflector-support interposed between the said reflector and water-chamber, conformed to the exterior shape of the said water-chamber and adapted to engage with and support the rear face of the reflector, a swivelled nut for engagement with the said stem, non-removably mounted in the reflector and projecting forwardly thereinto for manual operation from the inside thereof, and means for holding the reflector against rotation with respect to the said threaded 35 stem and reflector-support.
- 40 4. In an acetylene miner's lamp, the com-

bination with the lamp-body comprising a carbide-receptacle, and a water-chamber, of a threaded burner-stem projecting from the said water-chamber, a reflector, a reflector 45 supporting-shell interposed between the reflector and the said water chamber, and having its bottom conformed to the exterior conformation thereof, and means engaging with the said stem for holding the reflector 50 against the said shell, the said means being non-removably mounted in the reflector and projecting forwardly thereinto for manual operation from the inside thereof.

5. In an acetylene miner's lamp, the combination with the body and threaded burner-stem thereof, of a reflector, a reflector-supporting-shell interposed between the lamp-body and the reflector, a swivelled nut mounted in the reflector for engagement with the said stem, and means for holding the reflector against rotation with respect to the said shell.

6. In an acetylene miner's lamp, the combination with the body and threaded burner-stem thereof, of a reflector, a reflector-supporting shell interposed between the lamp-body and the reflector, and a swivelled nut mounted in the reflector for engagement with the said stem, the said reflector and shell being furnished with a locking-notch and complementary projection co-acting to prevent the reflector from turning with respect to the burner-stem.

In testimony whereof, I have signed this 75 specification in the presence of two subscribing witnesses.

ADOLPH C. RECKER.
